UNITED STATES PATENT OFFICE.

GORDON WILLIAMS, OF MOUNT CARMEL, CONNECTICUT.

WINDSHIELD.

Application filed February 12, 1926. Serial No. 87,771.

Fig. 1 is an inside view of a wind shield constructed in accordance with my invention.

Fig. 2 is a top or plan view of the same.

5 Fig. 3 is a side view, showing the shield locked in a partially-open position.

Fig. 4 is a similar view, showing the shield unlocked and in position to be further opened or closed.

10 Fig. 5 is a sectional view, showing the shield in its fully-closed position.

This invention relates to improvement in wind shields. In the more general construction of wind shields, provision is made at 15 each side for locking the shield in its various positions of adjustment, which locking mechanisms are independently operated, so that difficulty is experienced in opening or closing the shield. The object of this invention is to provide means, whereby the shield may be moved to any desired position with one hand, and the invention consists in the construction as hereinafter described and particularly recited in the 20 claims.

The sash 10 for the glass 11 is of substantially usual construction and is mounted in the usual frame 12, for this purpose the sash being provided on its upper face at 30 each side with knuckles 13 connected by pins 14 with knuckles 15 secured to the frame. The sash is provided on its inner face on each side with inwardly-projecting brackets 16 in which a transverse bar 17 is mounted, this bar being preferably angular in cross-section, and with rounded ends 18 which extend through segmental slots 19 formed in plates 20 secured to the frame.

Fixed to the bar 17 at each side is a 40 downwardly-extending arm 21 carrying a stud 22 to engage with locking-notches 23 opening into a clearance-slot 24, the stud 22 being yieldingly held in either of these notches by a spring 25 which is coiled 45 around the bar 17, one end bearing against the stud and the other against a pin 26 mounted in the brackets 16. Secured to the bar 17 to turn therewith and preferably in the center thereof is a hub 27 having bearing 50 ing in a bracket 28 secured to the inner face of the sash 10, the hub being formed with a downwardly-extending handle 29. Preferably, the bracket 28 will also be formed with a downwardly-extending grip 30. Preferably, also, the lower side of the sash 10 will be provided with a latch 31 adapted

to be turned into engagement with the frame to hold the shield in its closed position. When it is desired to open the shield, the latch 31 will be turned to disengage the 60 sash from the frame and then the lower edge of the sash may be pushed outward to the desired extent. In this outward movement, the stud 22 moves out of the uppermost notch and rides over the other notches until the shield comes to a rest, the spring 25 yielding to permit this movement and acting to turn the stud into engagement with the notches 23, and when thus adjusted, the shield is rigidly held. 65

When it is desired to close or partially close the shield, the handle 29 will be turned so as to turn the bar 17, and this turning of the bar 17 turns the arms 21, so as to move the studs 22 out of the notches 23, and holds 70 the studs out of the path of the notches until the bar 17 is released.

The grip 30 provides a convenient support for the hand and gives a bearing toward which the handle 29 is moved. Thus, 80 the shield can be adjusted or entirely closed by movement of the handle 29, which can be operated with one hand.

I thus provide simple means for adjusting and locking the wind shield in any desired position of adjustment. 85

It is obvious that the grip 30 may be omitted and it is also obvious that the bar 17 need not necessarily extend through the plates 20, but terminate within their inner faces, and it is obvious, also, that the spring for holding the studs in engagement with the notches may be varied. 90

I claim:

1. A wind shield, comprising a frame, a sash hinged at its upper edge thereto, a transverse bar mounted on said sash, plates secured to opposite sides of the said frame and extending inwardly therefrom, the said plates formed with locking-notches, arms 100 fixed to the said bar, studs carried by said arms to engage with said notches, and a handle fixed to said bar, whereby the bar may be turned.

2. A wind shield, comprising a frame, a sash hinged at its upper edge thereto, a transverse bar mounted on said sash, plates secured to opposite sides of the said frame and extending inwardly therefrom, the said plates formed with locking-notches, arms 105 fixed to the said bar, studs carried by said arms to engage with said notches, a handle 110

fixed to said bar, whereby the bar may be turned, and springs tending to force the studs into engagement with said notches.

3. A wind shield, comprising a sash and a frame to which the sash is hinged, a transverse rod supported by said sash, plates secured to opposite sides of the said frame and projecting inward therefrom, the said plates formed with locking-notches, arms fixed to opposite ends of said rod, studs mounted in said arms and adapted to engage with said notches, an intermediate support for said bar, and a handle mounted in said support and fixed to said bar.
- 10 4. A wind shield, comprising a sash and a frame to which the sash is hinged, a transverse rod supported by said sash, plates secured to opposite sides of the said frame and projecting inward therefrom, the said plates formed with locking-notches, arms fixed to opposite ends of said rod, studs mounted in said arms and adapted to engage with said notches, an intermediate support for said
- 15 20

bar, a handle mounted in said support and fixed to said bar, a grip stationary with said support, and springs tending to force the studs into the said notches.

25 30 35 40 45

5. A wind shield, comprising a sash and a frame to which the sash is hinged, a transverse rod supported by said sash, plates secured to opposite sides of the said frame and projecting inward therefrom, the said plates formed with locking-notches, arms fixed to opposite ends of said rod, studs mounted in said arms and adapted to engage with said notches, an intermediate support for said bar, a handle mounted in said support and fixed to said bar, a grip stationary with said support, springs tending to force the studs into the said notches, and a latch for interlocking the lower edge of the sash with the said frame.

In testimony whereof, I have signed this specification.

GORDON WILLIAMS.
